UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

INTERNAL-COMBUSTION ENGINE.

1,230,033.

Specification of Letters Patent. Patented June 12, 1917.

Application filed July 27, 1911. Serial No. 840,770.

To all whom it may concern:

Be it known that I, ANDREW L. RIKER, a citizen of the United States, and a resident of Bridgeport, county of Fairfield, State of Connecticut, (whose post-office address is Bridgeport, Connecticut,) have invented an Improvement in Internal-Combustion Engines, of which the following description, in connection with the accompanying drawings, is a specification, like characters on the drawings representing like parts.

This invention relates to internal combustion engines and particularly to the means for controlling the admission of fuel to the cylinder and the exhaust of the waste gases therefrom.

The invention will be best understood by reference to the following description when taken in connection with the accompanying illustration of one specific embodiment thereof, while its scope will be more particularly pointed out in the appended claims.

In the drawings:

25. Figure 1 is a sectional elevation taken through one cylinder of a double cylinder engine, the latter equipped with one form of my invention;

30. Fig. 2 is a plan in section taken on the line 2—2 in Fig. 1;

Fig. 3 is a plan view of a piston ring preferably employed in the described form of invention;

35. Fig. 4 an elevation of the same piston ring;

Fig. 5 is a detail in elevation showing the construction of the cylinder port;

40. Fig. 6 is a longitudinal section in elevation taken through a two-cylinder engine embodying the valve construction shown in Figs. 1 and 2;

Fig. 7 is a sectional elevation partly diagrammatic showing the piston and valve in their relative positions at one point in the 45 admission stroke;

Fig. 7^a is a section in plan showing the relation between the valve and the cylinder ports when the piston is at the point shown in Fig. 7;

50. Figs. 8, 9 and 10 are sectional elevations partly diagrammatic similar to Fig. 7 showing the piston and valve in different positions; and

Figs. 8^a, 9^a and 10^a are sections in plan

corresponding respectively to the positions 55 of the piston and valve shown in Figs. 8, 9 and 10.

Referring to the drawings and particularly to the embodiment of the invention shown in Fig. 1, the engine there illustrated 60 is provided with a fixed main cylinder 1 supported upon the crank casing 2. A piston 3 is provided connected by the connecting rod 4 to the crank 5 and crank shaft 6. The rear end of the cylinder is closed by the 65 cylinder head 7 which is bolted or otherwise fixedly secured to the end of the cylinder forming a gas tight joint and a gas tight closure for the end of the cylinder. The cylinder head has the portion 8 which projects into the rear end of the cylinder leaving an annular space between the same and the cylinder walls and has also the centrally arranged spark plug 9. The cylinder and cylinder head are both provided with the 70 75 usual water jacket 10.

In order to provide for a free admission of the gaseous fuel to the engine cylinder and preferably also to provide for a free exhaust of the waste gases therefrom, port 80 means are provided which are prolonged for a distance preferably equivalent to the major portion of the piston travel. While such port-means might be embodied in a single continuous port or a series of variously 85 positioned ports, herein is an intake opening provided by means of a port extending substantially the full distance of piston travel interrupted only by bridge pieces provided for the purpose of adding mechanical 90 strength to the cylinder where it is thus cut away. The port opening thus provided is rendered progressively available by the piston during its travel, so that, when the piston is near the forward end of the cylinder 95 leaving a large cylinder space to be filled or emptied, as the case may be, the port opening available in that position of the piston is correspondingly increased.

Referring particularly to Figs. 1 and 2, 100 the intake pipe is shown at 11 and this communicates with an admission space or chamber extending substantially the full length of the cylinder. To admit the fuel from the admission chamber to the cylinder, the latter is provided with a port 12 opening (shown in Fig. 5) extending approximately the full length of the piston travel so that

in the forward position of the piston (shown in full lines in Fig. 1) the upper edge of the piston overlies approximately the lower edge of the port 12 while in the rearward position of the piston (shown in dotted lines in Fig. 1) the upper edge of the piston overlaps the top of the port 12 by a slight amount. The port 12 is separated by one or more bridge pieces 13 (Fig. 5) so that the cylinder walls need not be unduly weakened by this prolonged port opening.

The exhaust pipe is represented at 14 and this communicates with an exhaust space or chamber similar to the admission chamber and opening into the cylinder through a prolonged port 15 similar in respect to its longitudinal extent to the admission port but offset therefrom by approximately 90°.

As will be observed, the prolonged admission and exhaust ports 12 and 15 are rendered progressively available or progressively unavailable by the piston as the latter moves forward and back respectively.

To render the admission and exhaust ports effective at appropriate times that is to say to uncover and cover the same at such points in the piston stroke that the engine will operate as a four-cycle engine, valve means are provided which positively open and close the admission and exhaust ports during the reciprocations of the piston.

While other forms of valve might be employed, herein I utilize for that purpose slide valves and preferably employ a single segmental valve having an arc-shaped form so that the same may be interposed as a sleeve between the fixed cylinder 1 and the piston and, by suitable actuating mechanism, be caused to uncover the ports at the required times.

While other forms of sleeves might be employed, herein I have utilized a large slide valve sleeve 16 adapted to turn and herein rotate continuously within the fixed cylinder 1 and to serve as the actual cylinder within which the piston 3 has sliding movement. As shown herein, the sleeve extends for the full length of the cylinder; the upper portion being contained between the walls of the cylinder and the inwardly projecting head portion 8, the packing ring 17 being provided between the head portion 8 and the sleeve to prevent the leakage of gases under compression or firing.

The lower part of the sleeve has an annular flange 18 which rests upon the thrust bearing 19 carried by the crank case, the upper side of the flange having attached thereto the hardened steel annular ring 20 engaging with the fixed annular ring 21 secured to the cylinder. The periphery of the flange is provided with gear teeth 22 which (see Fig. 6) mesh with the pinion 23 carried by the stud shaft 24, the latter driven from the crank shaft by either spiral

or bevel gears 25 and 26. The sleeve 16 is turned at a rate of one revolution for each two revolutions of the crank shaft.

In Fig. 6 I have shown a two-cylinder engine wherein the sleeve 16^a of the next adjacent cylinder of the pair is driven by intermeshing engagement of its gear 22^a with the gear teeth 22 of the sleeve 16. Obviously the sleeve 16^a being driven in a reverse direction, the relation of the ports in the cylinder will also be reversed. It will be evident that an engine composed of any desired number of cylinders may be constructed upon the same principle, the valve for each successive cylinder being turned by intermeshing engagement with the gear teeth for the preceding cylinder sleeve.

The walls of the sleeve 16 are closed except for a single port or succession of ports 27. These constitute in effect a single port coextensive in length with the admission and exhaust ports 12 and 15 and of substantially the same width as the exhaust port. To increase the mechanical strength of the sleeve the port 27 is sub-divided into a series of openings separated by the bridge pieces 28. The latter are preferably inclined as shown so that the piston and piston rings will readily slide over the same.

In order further to insure non interference between the piston and the ports 27, the former is provided with piston rings 29 of special construction. As shown in Figs. 3 and 4 the piston ring 29 instead of being split along a plane inclined to the plane of the ring is split along the plane 30 which is substantially tangential to the inside circumference of the ring and the rings are so placed in the piston that the line of separation is related to the direction of rotation of the sleeve as indicated by the arrow in Fig. 3. Through this provision the rotation of the sleeve cannot open or otherwise conflict with the separated edges of the ring.

In Figs. 7 to 19, inclusive, I have indicated the different positions which the valve assumes in different positions of the piston. In Figs. 7, and 7^a the valve and piston are shown in positions which they occupy during the admission stroke. At the end of the exhaust stroke the port 27 starts to uncover the admission port 12 and, as the piston moves forward, it renders available an increasing extent of the admission port opening. By the time the piston has completed half of its forward stroke, and therefore when it is moving at its maximum velocity, the entire width of the admission port has been uncovered by the valve. The admission port opening is preferably continued for the entire distance of piston travel so that it is available for the entire piston stroke. The cylinder port and the valve port may be so proportioned as to close the admission port at any desired time. Here-

in I have shown the proportions such that it is closed an instant or two after the termination of the forward or admission stroke of the piston, although it may be kept open 5 still longer or caused to close earlier if desired.

It will be observed that the provision of this prolonged port opening fills the cylinder space behind the piston with gaseous fuel as rapidly as the piston advances and that the gases are brought into the cylinder transversely behind the piston and it is unnecessary to cause them to deflect or bend after entering the cylinder to follow up the piston as the latter advances. Such deflection or bending of the gaseous fuel supply when the latter is admitted through ports at the rear of the cylinder tends to retard admission and is a frequent cause of incomplete admission and an inefficient cycle. As above stated in the described form of engine the maximum port opening is obtained at the maximum piston velocity and the size of the port opening varies approximately 25 with the piston speed and therefore is automatically proportioned to the requirements of admission.

In Figs. 8 and 8^a is indicated the position of the valve on the compression stroke which follows admission. It will be observed that near the completion of this stroke and at the commencement of the firing stroke which follows, when the highest pressures are reached, the port opening 27 of the valve is well displaced from the cylinder ports 12 and 15 so that leakage is effectively provided against. Preferably also the piston in its rearward position slightly overlaps the edges of the valve port 27 and the cylinder ports 12 and 15 so that under the conditions of maximum pressure in the explosion chamber additional protection is had against leakage.

In Fig. 9 conditions are represented during the firing or working stroke. The valve is here shown as moving toward the exhaust position but still covering the exhaust port.

In Figs. 10 and 10^a the position of the valve is shown during the succeeding rearward or the exhaust stroke. The valve is shown as uncovering the exhaust port 15 at approximately the end of the firing stroke and maintaining it open for the entire length of the exhaust stroke. As in the case of the admission stroke, the amount of valve opening at any given time is approximately proportional to piston speed and at the commencement of the exhaust stroke the entire length of exhaust port opening is available 55 being progressively covered however, by the piston as the latter moves back and the necessity for a large port opening decreases.

It will be observed that the location and proportions of the valve ports and the cylinder port may be variously chosen as it may

be required to advance or retard or increase or reduce the exhaust or admission. The proportions shown are merely for the purposes of illustration.

While the principles of the invention may be carried out in various ways and by the use of various forms of valves the form as shown is particularly advantageous since it is mechanically simple both as to its construction and its actuating mechanism and eliminates reciprocating parts.

While for the purposes of illustration I have here shown and described one form of the invention, it is to be understood that the same is submitted for illustrative purposes only and that extensive deviations may be made therefrom without departing from the spirit of the invention.

Claims:

1. An internal combustion engine having a cylinder, a piston, a prolonged port opening in said cylinder extending for substantially the distance of piston travel and adapted to be rendered progressively available by piston movement, and means apart from said piston for opening and closing said port opening.

2. An internal combustion engine having a cylinder, a piston, a succession of admission ports extending substantially the entire length of piston travel and adapted to be rendered progressively available by movement of the piston and means apart from the piston for uncovering said ports on each alternate forward stroke of the piston, but for closing them on the succeeding forward and the intermediate reverse piston strokes.

3. An internal combustion engine having a cylinder, a piston, a succession of admission ports in said cylinder extending for substantially the entire distance of piston travel and adapted to be rendered progressively available by the piston on forward movement thereof, and means for opening and closing said ports independently of the piston.

4. An internal combustion engine having a cylinder, a piston, a succession of admission ports in said cylinder extending for substantially the entire distance of piston travel and adapted to be rendered progressively available by the piston on forward movement thereof, and means comprising a ported rotary sleeve for opening and closing said ports independently of the piston.

5. An internal combustion engine having a cylinder, a piston, a succession of ports in said cylinder extending for substantially the distance of piston travel and adapted to be rendered progressively available by the piston; a ported slide valve between the piston and cylinder adapted to uncover said cylinder ports and a piston ring for said piston split along a plane transverse to the

plane of the ring and substantially tangential thereto.

6. In an internal combustion engine the combination with a cylinder having an intake chamber extending lengthwise the cylinder for substantially the entire piston travel, a succession of cylinder ports connecting said intake chamber with the interior of the cylinder, the opening provided by said ports being increasingly available on the forward movement of the piston for substantially the entire movement thereof, a ported sleeve interposed between the piston

and the cylinder and adapted to uncover said cylinder intake ports during one forward movement of the piston while maintaining the same covered during the next forward stroke and the intermediate reverse strokes thereof. 15

In testimony whereof, I have signed my name to this specification, in the presence of two subscribing witnesses.

ANDREW L. RIKER.
